[57] CLAIM

The ornamental design for an auto mat, as shown and described.

DESCRIPTION

FIG. 1 is a top plan view of an auto mat embodying my new design.

FIG. 2 is an enlarged fragmentary sectional view thereof taken on line 2—2 of FIG. 1.

The surface pattern which is partially shown for ease of illustration at the upper left corner of the rectangular area in FIG. 1 is understood to be continuous throughout said area.

The bottom of the auto mat is substantially flat and unornamented.
